United States Patent Office

Des. 193,010
Patented June 12, 1962

193,010

EXERCISING DEVICE

Carl Krauss, Chicago, Ill. (% Lakewood Engineering and Manufacturing Company, 212 N. Carpenter St., Chicago 7, Ill.)

Filed Oct. 19, 1959, Ser. No. 57,976

Term of patent 14 years

(Cl. D34—5)

FIG. 1 is a top plan view of an exercising device embodying my new design;

FIG. 2 is a bottom plan view thereof;

FIG. 3 is an enlarged side elevational view thereof;

FIG. 4 is an enlarged front or rear elevational view thereof; and

FIG. 5 is an enlarged cross sectional view taken on the line 5—5 of FIG. 1 and viewed in the direction of the arrows.

I claim:

The ornamental design for an exercising device, substantially as shown.
